UNITED STATES PATENT OFFICE.

GEORGE E. RANDLE, OF CLEVELAND, OHIO, ASSIGNOR TO THE FOOTE-BURT COMPANY, A CORPORATION OF OHIO.

WASHING MACHINE.

Application filed July 22, 1925. Serial No. 45,386.

The present invention relates to washing machines and especially to washing machines of the suction cup or pounder type.

In connection with such washing machines, it is desirable to mount the bells or cups on the yoke so that they are yieldable in a vertical direction. To accomplish this, it is usual to provide a spring mounting for the bells or cups.

10 An object of my invention is to provide an improved spring mounting for the bells or cups of a pounder type washing machine which, while serving efficiently its intended function, is simple in structure and capable 15 of being manufactured and assembled at a low cost.

20 A further object of my invention is to provide an improved construction wherein the means which holds the spring mounting assembled serves also to fasten the suction cup or bell to its stem.

25 A further object of my invention is to provide an improved construction wherein there are no openings through the top of the yoke whereby the yoke is left perfectly smooth on its top surface and presents no parts upon which clothes are likely to catch.

30 For a consideration of what I believe to be novel and my invention, attention is directed to the accompanying description and the claims appended thereto.

35 In the drawing, Fig. 1 is a side elevation, partly in section, of a structure embodying my invention; Fig. 2 is a detail sectional view of a spring mounting, the section being taken at a right angle to that of Fig. 1, and Fig. 3 is a sectional view of a modification.

40 Referring to the drawing, 1 indicates the plunger rod of a pounder or suction cup type washing machine and 2 indicates the yoke which is mounted on the plunger rod and carries the suction cups or bells at the ends of its arms 3. The washing machine 45 mechanism for actuating the plunger rod may be of any suitable type. For example, it may be of the type or construction shown in my Patent No. 1,520,886, dated December 30, 1924. The yoke may comprise any suitable number of arms 3, for example, three arms or two arms. It is preferably adjustably mounted on the plunger rod, being held by a spring-pressed pin 4 adapted to engage in any one of a number of openings

5 in the upper end of the plunger rod. The 55 head of the pin which enters openings 5 is indicated at 6 and the spring for holding the pin is indicated at 7.

At the end of each yoke arm is a downwardly-facing socket 8 which is closed at 60 the top by a smooth wall 9. Wall 9 is rounded so as to present a pleasing appearance and leave no sharp corners upon which clothes might catch. In the wall of socket 8 is a transverse opening 10 in which is located a pin 11, the pin fitting the opening with a drive fit. In socket 8 is a tubular stem 12 having a vertically-elongated slot 13 through it, through which pin 11 passes, the stem being thus hung on the pin. On 70 the lower end of stem 12 is a dished collar or flange 14 against which the suction cup or bell 15 is held. The lower end of tubular stem 12 is threaded and screwing into it from below is a plug 16 having a flange 17 75 which engages the suction cup or bell 15 and serves to attach it to stem 12. Dished collar or flange 14 has a radius of curvature less than that of the bell or suction cup so that when plug 16 is screwed up to fasten 80 bell 15 to collar 14, the bell will be pulled tightly into engagement with the flange at the edge of the flange. This gives a tight connection between the two parts and serves to hold the bell from turning. As an additional means for holding the bell from turning, I may provide a depression 18 in collar 14 into which a raised portion 19 in the bell fits. 85

Located in tubular stem 12 between the inner end of plug 16 and pin 11 is a spring 90 20 which is held under compression by the plug. Between the upper end of the spring and pin 11 is arranged a disk 21 having a conical projection 22 on its upper surface which fits in a groove 23 surrounding pin 11. This disk serves as a lock for pin 11 to prevent the pin from coming out. It serves also as a seat for the upper end of the spring. In flange 17 of plug 16 are suitable 95 openings 24 to receive a wrench for screwing the plug into place.

100 With the above-described arrangement, it will be seen that the entire structure is held assembled by the flanged plug 16 and that 105 no separate fastening means is required for attaching bell 16 to stem 12. This means that the structure can be quickly and easily

assembled and that no special skill or special tools are required for the operation. Also, as will be noted, the structure comprises a minimum number of parts.

5 In assembling the structure, stem 12 is inserted into socket 8 and pin 11 is then driven through opening 10 and slot 13. Following this disk 21 is dropped into stem 12 followed by spring 20. Bell 15 is then 10 placed in position in dished flange 14 and plug 16 screwed into place. The screwing of the plug into place serves to fasten the entire structure together and to put spring 20 under the desired degree of compression.

15 In Fig. 3 is shown a modification wherein pin 11^a corresponding to pin 11 of Figs. 1 and 2 is threaded on its inner end as is indicated at 25 and screws into an opening 20 in arm 3. With this arrangement the pin is held by the screw threads so that a locking disk such as the disk 21 of Figs. 1 and 2 need not be used. Otherwise, the arrangement of Fig. 3 is the same as that of Figs. 25 1 and 2.

20 Spring 20 is held under the desired compression by plug 16 and serves normally to hold the suction cup from vertical movement. When the upward pressure on the suction cup is excessive, however, the spring yields to permit stem 12 to move upward in socket 8, the spring being compressed against pin 11. Slot 13 is of a length to permit of the desired amount of axial movement of 30 stem 12 in socket 8.

25 In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

40 45 What I claim as new and desire to secure by Letters Patent of the United States, is:—

1. In a suction cup washing machine, a member having a socket open at its lower 50 end, a tubular stem projecting into said socket, said stem having an elongated slot in its wall, a pin which extends through the wall of said socket and through said slot, a plug in the lower end of the stem, a spring 55 located between said plug and pin, said tubular stem having an internal diameter such that the spring may be inserted from the outer end of the stem, and a suction cup carried by the stem.

60 2. In a suction cup washing machine, a member having a socket open at its lower end, a tubular stem projecting into said socket, said stem having an elongated slot in its wall, a pin which extends through 65 the wall of said socket and through said

slot, a dished flange on the stem, a suction cup, a spring in the stem, and a plug in the lower end of the stem which serves to attach the suction cup to the stem and to hold the spring in place.

70 3. In a suction cup washing machine, a member closed at its upper end and having a downwardly extending socket, a tubular stem which projects into the socket, the lower end of said stem being threaded, means for holding the stem in the socket, a dished flange on the lower end of the stem, a suction cup, and a flanged plug which threads into the lower end of the stem for fastening the cup to the stem and in engagement with said flange.

75 4. In a suction cup washing machine, a member closed at its upper end and having a downwardly opening socket, a tubular stem which projects into the socket, the lower end of said stem being threaded, means for holding the stem in the socket, a dished flange on the lower end of the stem, a section cup, a flange plug which threads into the lower end of the stem for fastening the cup to the stem and in engagement with said flange, the radius of curvature of the bell being greater than that of the flange whereby the flanged plug draws the bell into tight engagement with the edge of the flange.

80 85 90 95 100 5. In a suction cup washing machine, a member having a socket, a tubular stem which projects into the socket, a spring in the stem, a suction cup, a plug in the lower end of the stem which holds the spring in the stem and fastens the cup to the stem, and means in the socket against which the upper end of the spring engages.

105 6. In a suction cup washing machine, a member having a socket, a tubular stem which projects into the socket, means for holding the stem in the socket, said means permitting of limited axial movement of the stem in the socket, a suction cup carried by the stem, a spring in the stem, said tubular stem having an internal diameter such that the spring may be inserted from the outer end of the stem, and a plug which closes the outer end of the stem and holds the spring under compression.

110 115 120 125 7. In a suction cup washing machine, a member having a socket, a tubular stem which projects into the socket and has a limited axial movement therein, a suction cup carried by the stem, a spring in the tubular stem adapted to be inserted therein from the outer end of the stem, and a plug in the outer end of the stem which engages directly with the spring to hold it under compression in the stem.

In witness whereof, I have hereunto set my hand this 20th day of July, 1925.

GEORGE E. RANDLES.
